(57) CLAIM

The ornamental design for a drain stopper, as shown and described.

DESCRIPTION

FIG. 1 is a front right perspective view of a drain stopper in accordance with the present invention, whereby the plunger is shown in the closed position;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof; and,

FIG. 9 is a front right perspective view thereof, whereby the plunger is shown in the open position.

The broken lines in the drawings depict portions of the drain stopper and form no part of the claimed design.

The use of the symbol on the design article forming part of the disclosure of the claimed design is a registered trademark of DaVinci CSJ, LLC.

1 Claim, 6 Drawing Sheets
